**AWNNG GUARD ROLLER ASSEMBLY FOR
RECREATIONAL VEHICLE DOORS OR THE
LIKE**

Ray E. Mullis, Greensboro, N.C., assignor to Pine State
Tool and Machine Co., Inc., Greensboro, N.C.

Filed June 18, 1973, Ser. No. 371,059

Term of patent 14 years

Int. Cl. D8—09

U.S. Cl. D8—238

FIG. 1

FIG. 6

FIG. 2

FIG. 3

FIG. 4

FIG. 5

FIG. 1 is a perspective view of an awning guard roller assembly for recreational vehicle doors or the like showing my new design;

FIG. 2 is a side elevational view of the roller assembly;

FIG. 3 is a front view of the assembly;

FIG. 4 is a side elevational view of the roller assembly opposite to that of FIG. 2;

FIG. 5 is a rear view of the assembly; and

FIG. 6 is a top plan view of the assembly.

I claim:

The ornamental design for an awning guard roller assembly for recreational vehicle doors or the like, as shown and described.
